UNITED STATES PATENT OFFICE.

JOSEPH HARRIS, JR., OF BOSTON, MASSACHUSETTS.

TIRE-HEATING FURNACE.

SPECIFICATION forming part of Letters Patent No. 350,131, dated October 5, 1886.

Application filed May 22, 1886. Serial No. 202,990. (No model.)

To all whom it may concern:

Be it known that I, JOSEPH HARRIS, Jr., a citizen of the United States, residing at Boston, in the county of Suffolk and State of Massachusetts, have invented a new and useful Improvement in Apparatus for Heating Tires, of which the following is a specification.

My invention relates to an improvement in apparatus for heating wheel-tires by petroleum or other hydrocarbon oil, by means of which several tires of different sizes can be heated at the same time, thereby effecting a great saving of labor and fuel; and the invention consists in certain details of construction, hereinafter fully described, and set forth in the claims.

In the accompanying drawings, Figure I is a perspective view of a heating apparatus embodying my invention. Fig. II is a vertical section of the same on an enlarged scale. Fig. III is a plan view of the base or oil-receptacle. Fig. IV is a perspective view of one section of the top or cover. Fig. V shows a modification of the base or oil-receptacle.

25 A represents the base or oil-receptacle, supported on suitable legs, *a*. The bottom of the receptacle is provided with a number of nipples, *B*, having holes *b* through each one, so as to admit air to the interior to aid in supporting combustion. The upper edges of the base *A* are provided with offsets or ledges *d*, for receiving and holding in position the several sections *C* of the top or cover. The sections *C* are each provided at one end with a socket, 35 *c*, into which the end of the adjacent socket is inserted, so that when all the sections are in position they will be secured together and constitute a solid cover. Each of said sections *C* is provided with two radial flues or openings, *D* *D*, extending above the top of the sections, through which the smoke and waste products of combustion escape. The curved sections are each cast in one piece.

40 *E* *E* are bars upon which the tires to be heated are supported. The said bars extend across the upper part of the base *A*, and are let into recesses *e* in the ledges *d* on the circumference and the inner circular edge of the base *A*.

45 *F* is a small perforated pipe extending around the inside of the base *A*, and to which is connected a pipe, *G*, provided with a funnel-shaped mouth-piece, *H*, for supplying oil-

chamber in case the oil in the base should become exhausted while the tires are being heated. 55

In Fig. V I have shown a modification of the method of supplying air to the interior of the base *A*. In this case the nipples *B* are dispensed with, and holes *b*' are made around the upper edge of the oil-receptacle. 60

The operation is as follows: The oil-receptacle or base *A* being supplied with the requisite quantity of oil and the bars *E* placed in position, the tires are laid upon said bars and the sections *C* placed in position, as shown in Fig. I. The oil is then ignited, and air passing up through the holes *b* in the nipples *B*, which extend above the surface of the oil, aid the combustion, and the portions so extended become heated and serve to vaporize the oil, 65 thus adding to the heating quality. The products of combustion pass off through the flues *D*. When the tires are sufficiently heated, which takes but a very short time, the sections *C* are taken off and the tires removed; or one tire can be removed and the sections replaced to keep the remaining tires hot, if required. 70 The inner sides of the sections *C* serve to deflect the heat and throw it down upon the tires while being heated. 75

What I claim as my invention is—

1. A tire-heating apparatus consisting of a base or oil-receptacle, *A*, in combination with a cover composed of sections *C*, each provided with radial flues or openings *D* *D*, as shown 85 and described.

2. In a tire-heating apparatus, the circular base or oil-receptacle *A*, provided with perforated nipples *b*, all cast in one piece, as and for the purpose set forth. 90

3. In combination with the oil-receptacle *A*, the perforated oil-supply pipe *F*, provided with a mouth-piece, *H*, as shown and described.

4. In a tire-heating apparatus, the sections *C*, provided with radial flues or openings *D*, 95 and connected together to form a circular cover for the heating-chamber, substantially as shown and described.

In testimony whereof I have signed my name to this specification in the presence of two subscribing witnesses. 100

JOSEPH HARRIS, JR.
